PICNIC GRILL

Warren P. Miller, Norman R. Miller, and
Ralph E. Williams, Anderson, Ind.

Application January 4, 1950, Serial No. 6,996

Term of patent 14 years
(Cl. D81—10)

To all whom it may concern:

Be it known that we, Warren P. Miller, Norman R. Miller, and Ralph E. Williams, citizens of the United States of America and residents of Anderson, county of Madison, State of Indiana, have invented a new, original, and ornamental Design for a Picnic Grill, of which the following is a specification, reference being had to the accompanying drawings, forming part hereof, in which

Fig. 1 is a top plan view of a picnic grill, showing our new design;

Fig. 2 is a front elevation thereof;

Fig. 3 is a rear elevation thereof;

Fig. 4 is a fragmentary end elevation of the grill with the tubular upright broken away for convenience of illustration; and

Fig. 5 is a fragmentary portion of Fig. 1 but drawn to a greatly enlarged scale in order to more clearly illustrate the design of the top grill surface.

We claim:

The ornamental design for a picnic grill, as shown.

WARREN P. MILLER.
NORMAN R. MILLER.
RALPH E. WILLIAMS.
